CONTROLLING MEANS

John L. Stoughton and Walter S. Landon, Detroit, Mich., assignors to Detroit Lubricator Company, Detroit, Mich., a corporation of Michigan

Application February 11, 1942, Serial No. 430,428

13 Claims. (Cl. 158—28)

This invention relates generally to controlling means and is adapted among other uses to control the flow of fuel and air to a fluid fuel burner.

One object of this invention is to provide means responsive to changes in one condition to cause a change in a second condition.

Another object is to provide a control means for a fluid fuel burner for modulating the amounts of air and fuel to provide a desired combustible mixture.

Another object is to provide in such a control means, means to modulate the flow of fuel in accordance with changes in air flow.

Other objects will be apparent from a reading of the specification.

The invention consists in the improved construction of and combination of parts to be more fully described hereinafter and the novelty of which will be particularly pointed out and distinctly claimed.

In the accompanying drawing there is fully and clearly illustrated a preferred embodiment of the invention, in which drawing—

Figure 1 is a diagrammatic view of an oil burning system embodying the invention.

Fig. 2 is a diagrammatic view showing a modified burner system embodying the invention.

Referring to Figure 1 of the drawing by characters of reference the numeral 1 designates generally a fluid fuel burner such as is known in the art as a "pot type" burner having an inner or vaporizing chamber 2 and an outer chamber 3 surrounding the chamber 2 for supplying air to the chamber 2 through a series of holes 4. Burners of this type are well known to the art and a more complete description thereof is not deemed necessary. A pressure or centrifugal type fan means 5 is driven by an electric motor 6 and discharges air under pressure into a conduit means 7 opening into the chamber 3 through its bottom wall for supplying a quantity of air under pressure to the chamber 3 from whence it flows through the holes 4 into the chamber 2.

Fuel such as oil is supplied from a suitable source of supply (not shown) through a conduit 8 leading to a strainer chamber 9 carried integrally with the bottom wall 10 of a fuel controlling means generally designated 11. The means 11 comprises a chambered casing having a fuel receiving reservoir 12 and a control chamber 13 positioned above the reservoir 12 and separated therefrom by a plate-like member 14. Fuel is admitted from the strainer chamber 9 through a float controlled inlet valve means 15 which is operable to maintain the fuel level within the

reservoir 12 substantially at the line L—L. The controlling means 11 has an outlet 16 opening from the reservoir 12 and opening into a fuel conduit 17 which conveys the fuel from the reservoir 12 to the chamber 2 of the fuel burner 1 for discharging the fuel adjacent the bottom wall of the chamber 2.

A reciprocal movable valve member 18 has the usual reduced diameter end portion received within an outlet port in the outlet 16 and has a V-shaped slot 19 cooperable with the outlet port for controlling the flow of fuel supplied by the controlling means 11 to the burner 1. Upward movement of the member 18 acts to position a greater area of the slot 19 above the outlet port to provide for increased fuel flow and downward movement acts to reduce the fuel flow to the burner 1. A helical coil compression spring 20 is positioned concentric with the valve member 18 and has its upper end portion abutting the underside of the plate-like member 14 and has its lower end portion abutting a flange 21 secured to the valve member 18 so that it exerts a force to urge the valve member 18 downward toward a flow reducing position. The valve member 18 has a stem portion 22 extending from the reservoir 12 through an aperture in the plate-like member 14 and into the chamber 13. Downward movement of the valve member 18 is limited by a minimum fire adjustable stop member 23 positioned in the chamber 13 and which has at its lower end portion a radially outwardly extending flange 24 which is engaged by a radially outward extending flange 25 of the valve member stem portion 22. The stop member 23 is screw threaded secured in an abutment or flange 26 extending into the chamber 13 from the front wall of the means 11. The upper end of the stem portion 22 is of reduced diameter and is received within an aperture extending through the flange 26 to guide the upper end of the valve member in its reciprocal movement. The upward movement of the valve member 18 is limited by engagement of the flange 25 with a radially outwardly extending flange 27 on the lower end portion of a high fire adjustable stop member 28.

The valve member 18 is moved upward against the force of the spring 20 by a bimetallic power element 29 having a substantially cylindrical heat sensitive portion 30 with a longitudinally extending side wall slot. The portion 30 adjacent its slot is rigidly secured as by welding to a supporting member 31 which is carried by the upper face of the plate-like member 14 and within the chamber 13. A lip portion 32 extends from the portion

30 adjacent the other edge of the slot from the member 31 and is positioned to engage the under-face of the flange 25. Normally the upward force exerted by the lip portion 32, with the portion 30 at normal ambient temperature, is insufficient to move the valve member 18 upward against the downward force of the spring 20 so that the flanges 24 and 25 remain in engagement. An electric resistance heater unit 33 is positioned within the cylindrical heat sensitive portion 30 and is operable to supply heat to the portion 30 so that the temperature of the portion 30 may be raised sufficiently to cause the lip portion 32 to exert an increased upward force on the flange 25 sufficient to overcome the downward force exerted by the spring 20 thereby to move the valve member upward causing an increased supply of fuel to be passed by the slot 19 to the conduit 17 for flow to the burner 1.

Air flow from the fan means 5 through the conduit means 7 to the burner 1 is regulated or controlled by a damper 34 pivoted as at 35 and having an extending operating arm 36. A bimetallic power element 37 similar to the element 29 has a substantially cylindrical portion 38 supported on the supporting member 39 carried on a fixed abutment 40 rigid with the conduit means or air duct 7 and has a lip portion 41 engaging the top surface of the arm 36. Air pressure acting on the damper 34 acts to urge it in a counter-clockwise direction about the pivot 35 to maintain the arm 36 in engagement with the lip portion 41. If desired, a biasing spring urging the damper 34 toward open position may be used. An electric resistance heater unit 42 is positioned in the cylindrical portion 38 and is operable to supply heat to the portion 38 so that the lip portion 41 will be moved to allow the damper 34 to pivot in a counter-clockwise direction thereby to permit a greater flow of air to the burner 1.

An electric resistance unit 43 having a high rate of increase in resistance with increase in temperature is positioned within the duct 7 intermediate the damper 34 and burner 1 and in a position to be in the path of the average air velocity flowing to the burner 1. A transformer 50 has a primary coil 51 connected by lead wires 52 and 53 to a suitable source of electrical energy and has a secondary coil 54 having its ends secured to secondary terminals 55 and 56. Lead wires 52 and 53 connect the lead wires 52 and 53 respectively to the motor 6 which remains energized as long as the transformer 50 is energized. The terminal 55 is connected by a lead wire 57 to one terminal 58 of a modulating type thermostat diagrammatically shown at 59 and comprising a resistance element 60 and a bimetallic temperature sensitive blade or member 61. The member 61 wipes against the element 60 making an electrical circuit therewith which utilizes more or less of the resistance element 60 to form a variable resistance having its resistance dependent upon the temperature of the medium surrounding the blade 61. The other terminal 62 of the thermostat 59 is connected by a lead wire 63 to one terminal of the unit 42. A lead wire 64 connects the other terminal of the unit 42 to the terminal 56. A branch lead wire 65 of the lead wire 64 is connected to one terminal of the unit 43 which has its other terminal connected by a lead wire 66 to one terminal of the unit 33. The other terminal of the unit 33 is connected by a lead wire 67 to the terminal 55.

The operation of the apparatus of Figure 1 is 75

as follows: The thermostat 59 is preferably positioned within and responsive to the temperature of a room or other enclosed space which is heated by the burner 1. Upon decrease in temperature of the space the bimetallic blade 61 warps to the left (see Fig. 1) to reduce the resistance offered to current flow through resistance 60 of the thermostat 59. A greater current then flows from the secondary coil 54 through lead wire 57, thermostat 59, lead wire 63, unit 42 and lead wire 64 back to the secondary coil 54. This greater current causes the cylindrical portion 38 of the element 37 to increase in temperature, thereby raising the lip portion 41 allowing the damper 34 to move further toward open position to increase the rate of air flow to the burner 1. It is to be noted that the fan means 5 is operated continuously. This increased rate of air flow to the burner 1 acts to cool the resistance unit 43. Cooling of the resistance unit 43 acts to reduce the resistance thereof to current flow and thereby reduces the voltage drop thereacross and increases the voltage drop across the unit 33 to cause the unit 33 to heat the cylindrical portion 30 of the element 29 to a higher temperature. The increase in temperature of the cylindrical portion 30 causes the lip portion 32 to move upward lifting the valve member 18 against the force of the spring 20 to increase fuel flow to the burner 1 proportionately to the increased air flow. The increased flow of fuel and air to the burner 1 causes the output thereof to increase and raise the temperature of the space in which the thermostat was positioned. As the temperature of this space increases the bimetallic blade 61 warps toward the right (Fig. 1) thereby increasing the resistance to current flow through the thermostat 59 and reducing the current flow through the unit 42. Reduced current flow through the unit 42 reduces its heating effect on the cylindrical portion 38 of the element 37 causing the lip portion 41 to move downward thereby moving the damper 34 toward closed position reducing the flow of air through the conduit means 7 to the burner 1. As the flow of air through the conduit means 7 is reduced, the cooling effect of this air flow on the unit 43 decreases, thereby allowing the unit 43 to increase in temperature. This increase in temperature of the unit 43 causes its resistance to increase, thereby increasing the voltage drop thereacross and decreasing the voltage drop across the unit 33. This decreased drop across the unit 33 causes the temperature of the cylindrical portion 30 to be reduced, thereby moving the lip portion 32 downward so that the spring 20 will move the valve member 18 toward closed position to reduce the fuel flow to the burner 1 in accordance with the reduced air flow to the burner 1.

60 It may now be seen that by this invention there is provided a means for balancing the fuel flow in accordance with the air flow to a burner to maintain a desired combustion in the burner the magnitude of which varies in accordance with the temperature of the heated space and which combustion rate is modulated to maintain the temperature of the space within a predetermined desired range.

65 Referring to Figure 2 of the drawing the numeral 70 designates a pressure or centrifugal type fan means driven by an electric motor 71 and supplying air under pressure through a conduit means or duct 72 to a fluid fuel burner (not shown) similar to the burner 1 of Fig. 1. Fluid

fuel for the burner is controlled by means of a valve member 73 which cooperates with a valve port 74 and which is intercalated in the fuel supply to the burner similar to the intercalation of the valve member 18 in the fuel supply to the burner 1. The valve member 73 has a stem portion 75 extending upwardly through an aperture in a supporting member 76 held in fixed position relative to the port 74. A helical coil spring 77 is positioned concentric with the stem portion 75 and has its lower end portion abutting the upper face of the supporting member 76 and its upper end portion abutting a radially outward extending flange 78 of the stem portion 75. The spring 77 acts due to its expansive force to urge the valve member 73 in an upward direction to increase the flow of fuel through the port 74. The upper end portion 79 of the stem portion 75 is of reduced diameter and provides a shoulder 80 at its intersection with the normal diameter portion of the stem portion 75.

A plate-like supporting member 81 is held rigid with the fixed supporting member 76 and has a first screw threaded aperture therethrough aligned with said valve member for receiving in screw-threaded relation an adjustable high fire stop member 82 against which the top end portion of the valve member 73 abuts to limit its upward movement away from the port 74. The supporting member 81 has a second aperture extending therethrough in which is positioned a collar member 83 having spaced shoulders 84 and 85 engageable respectively with the lower and upper surfaces of the member 81. The distance between the shoulders 84 and 85 is so proportioned relative to the thickness of the plate-like member 81 that the collar member 83 can have predetermined reciprocal movement in the aperture, the purpose of which is to be described hereinafter. The collar member 83 has a screw threaded central aperture extending therethrough in which is screw threaded a thrust member 86 which extends downward therefrom toward the wall having the port 74 and which has at its lower end portion a flanged head 87. Intermediate the head 87 and the collar member 83 and screw threaded to the member 86 is a cylindrical abutment member 88 having a portion of its side wall flattened as at 89 to provide a shoulder 90. A helical coil spring 89a is positioned concentric with the member 86 and is held under compression between the head 87 and the member 88 to prevent undesired relative rotation between the members 86 and 88. Numeral 91 designates generally a bimetallic heat actuated power element similar to the element 29 and having a substantially cylindrical portion 92 carried adjacent its split wall by a supporting member 93 rigidly secured to a fixed member 94 rigid with the fixed member 76 and having a lip portion 95 extending from the cylindrical portion 92. The lip portion 95 extends adjacent the flattened wall 89 overlying the shoulder 90 and terminating so that its end portion engages the shoulder 80 of the valve member 73. The fixed member 94 has a downwardly projecting portion 96 in which is positioned a rod or fulcrum member 97 which has its longitudinal axis extending substantially perpendicular to the longitudinal axis of the thrust member 86. A switch actuating lever member 98 has one end portion pivotally secured to the rod 97 and has secured to its other end a strip 99 of insulating material such as "Micarta" for engaging a current conducting movable blade 100 of a switch diagrammatically shown and designated 75

101. Upon counter-clockwise rotation of the lever member 98 the strip 99 acts to rotate the blade 100 clockwise, thereby causing contact members 102 and 103 to complete an electric circuit 5 through the switch 101. The lever member 98 is urged in a counter-clockwise direction by a spring 104 which has its coiled portion surrounding the rod 97 and one end portion engaging the underside of the lever member 98 and its other end portion engaging the lower wall of the fixed member 94. The lever member 98 has a semi-circular upwardly extending abutment 105 which engages the head 87 and which is held in engagement therewith by the spring 104. The predetermined permissible reciprocal movement of the collar member 83 is so chosen that movement thereof from the position in which the shoulder 85 engages the member 81 to the position in which the shoulder 84 engages the member 81 is sufficient to cause the lever member 98 to rotate sufficiently to move the contact members 102 and 103 into engaging relation. Conversely upon downward movement of the collar member 83, the predetermined distance is enough to separate the contact members 102 and 103. The thrust member 86 is screwthreaded relative to the collar member 83 with the shoulder 85 in engagement with the supporting member 81 until the switch is moved to circuit breaking position, i. e., contact members 102 and 103 in a separated position. Subsequent to this adjustment, the collar member 83 is soldered to the thrust member 86 to hold the members 83 and 86 in their adjusted position.

Referring again to the bimetallic power element 91, the lip portion 95, with the cylindrical portion 92 at normal ambient temperature, exerts a sufficient force in the downward direction to overcome the upward force of the spring 77 and the counter-clockwise force of the spring 104 so that the shoulder 85 is maintained in engagement with the supporting member 81. This position of the thrust member 86 maintains the switch 101 in open circuit position and the valve member 73 is maintained by the lip portion 95 in minimum fire position. The minimum fire position may be adjusted to any desired fire by rotating the thrust member 86 so that the cylindrical member 88 which is held against rotation by the lip portion 95 of the element 91 due to the engagement of the flattened wall 89 with the edge of the lip portion 95. Rotation of the thrust member 86 in one direction will cause the cylindrical member 88 to be moved upward on the member 86 to increase the low fire and rotation in the opposite direction will cause the member 88 to be moved downward on the member 86 to decrease the low fire. The operation of the switch 101 by the thrust member 86 will not be altered by this adjustment because the collar member 83 is held against changing its position relative to the thrust member 86 by the solder.

A second bimetallic heat actuated power element 106 is similar to the element 91 and has a substantially cylindrical portion 107 and a lip portion 108. The portion 107 is secured adjacent one side of its split to a supporting member 109 carried by a fixed member 110 rigidly positioned relative to the supporting member 76. The lip portion 108 is carried by the cylindrical portion 107 adjacent the other side of its split. The extending free end portion of the lip portion 108 overlies and is engageable by the shoulder 80 of the valve member 73 and acts to limit opening movement of the valve member 73 under the influence of the element 91. An intermediate fire

adjustable stop member 111 is screwthreaded within an aperture in the plate-like member 81 and has at its lower end portion a radial outwardly extending flange 112 against the upper face of which the lip portion 108 is operable to seat to limit the downward movement of the portion 108. At normal ambient temperatures the lip portion 108 exerts sufficient downward force so that upon engagement of the shoulder 80 therewith and upon disengagement of the lip portion 95 with the shoulder 80, the upward force of the spring 77 is not sufficient to move the valve member 73 further in an upward direction.

The element 91 is actuated by means of an electric resistance heater unit 113 positioned in the cylindrical portion 92 and which acts to raise the temperature thereof sufficiently so that the spring 77 will be able to move the valve member 73 upward until the shoulder 80 engages the lip portion 108. Continued energization of the unit 113 will continue to raise the temperature of the element 91 and cause the lip portion 95 to leave the shoulder 80 and move out of the path of movement of the valve member 73. The element 106 is actuated by an electric resistance heater unit 114 positioned within the cylindrical portion 107. Upon energization, the unit 114 acts to raise the temperature of the portion 107 to permit the lip portion 108 to control the positioning of the valve member 73 by the spring 77. The higher the temperature to which the portion 107 is heated the further the valve member 73 will be moved from the port 74 and the greater the fuel flow to the burner; the maximum flow being limited by the engagement of the valve member 73 with high fire stop member 82.

The electric resistance unit 114 has a low rate of increase in resistance with increase in temperature while an electric resistance unit 115 positioned in the duct 72 has a high rate of increase in resistance with increase in temperature relative to the unit 114. The unit 115 is positioned within the duct 72 so that it is in the path of the average flow velocity through the duct 72.

Electrical energy is supplied through lead wires 116, 117 to a primary coil 118 of a transformer 119. The transformer 119 has a secondary coil 120, one terminal of which is connected by means of a lead wire 121 to one terminal 122 of a room thermostat diagrammatically shown at 123. The other terminal of the secondary coil 120 is connected to a terminal 124. A lead wire 125 connects the terminal 124 to one end of the resistance unit 115. The other end of the unit 115 is connected by means of a lead wire 126 to one end of the unit 114. The other end of the unit 114 is connected by means of a lead wire 127 to a second terminal 128 of the room thermostat 123. The room thermostat 123 has a pair of engageable contact members 129 and 130 which are moved into engagement with each other to complete an electrical circuit through the thermostat 123 upon decrease in temperature of its bimetallic blade 131. A lead wire 132 connects the terminal 124 to one end of the resistance unit 113 and the other end of the resistance unit 113 is connected by means of a lead wire 133 to the terminal 128.

A branch lead wire 134 of the lead wire 116 is connected to one terminal of the electric motor 71. The other terminal of the electric motor 71 is connected by means of a lead wire 135 to the switch blade 100 which carried the contact member 102. The contact member 103 of the switch 101 is connected by means of a lead wire 136 to the lead wire 117.

The operation of the apparatus as disclosed in Fig. 2 is as follows: The burner (not shown) acts to heat the space or room in which the room thermostat 123 is positioned. Upon decrease in temperature of the air surrounding the thermostat 123 to a predetermined minimum temperature, the bimetallic blade 131 will move the contact member 130 into engagement with the contact member 129, thereby completing the following electrical circuits: Current flows from the secondary coil 120 of the transformer through lead wire 121, thermostat 123, lead wire 133, resistance unit 113, lead wire 132 back through the terminal 124 to the transformer secondary coil 120. Current also flows from the transformer secondary coil 120 through lead wire 121, thermostat 123, lead wire 127, unit 114, lead wire 128, unit 115, lead wire 125, and terminal 124 back to the transformer secondary coil 120. Current flow through these two circuits acts to cause the resistance units 113, 114 and 115 to increase in temperature. As the temperature of the unit 113 increases, the temperature of the cylindrical portion 92 of the element 91 will increase and upon a predetermined increase of temperature of the portion 92 the lip portion 95 will be moved upward to permit the springs 77 and 104 to move the valve member 73 toward open position and to move the switch 101 to closed position respectively. During the time interval required to raise the temperature of the portion 92 sufficient to permit the valve member 73 to be moved upward, the temperature of the unit 115 will have increased sufficiently so that the voltage drop thereacross will be so great that the voltage drop across the unit 114 will be reduced sufficiently so that the unit 114 is ineffective to heat the cylindrical portion 107 of the element 106 sufficiently to cause the lip portion 108 to move out of engagement with the flange 112 of the intermediate fire adjustment member 111. The intermediate adjustment member 111 is preferably so adjusted that the fuel supplied by the valve member 73 when the member 73 is limited in its movement by member 111 may be burned in the burner either at forced draft or natural draft conditions. Upon closure of the switch 101 an electrical circuit will be completed from the lead wire 136, through the switch 101, through lead wire 135, through the motor 71 and lead wire 134 back to the lead wire 116, thereby energizing the motor 71 causing the fan means 70 to supply air under pressure through the duct 72 to the burner (not shown). This air flow through the duct 72 will act to reduce the temperature of the resistance unit 115, thereby decreasing the voltage drop thereacross and increasing the voltage drop across the unit 114. This increased voltage drop across the unit 114 permits the unit 114 to raise the temperature of the portion 107 sufficiently to permit the lip portion 108 to move upwards so that the valve member 73 will be moved toward open position by the spring 77. Upon sufficient cooling of the unit 115 by the air flowing through the duct 72, the voltage drop across the unit 114 will increase sufficiently so that the lip portion 108 will permit movement of the valve member 73 to its maximum open position, i. e., engagement of the valve member 73 with the high fire stop member 82. Should the air supplied by the fan means 70 to the burner vary for any reason whatsoever the cooling effect of the air flow will vary and the temperature of the unit 115 will vary to change the temperature of the element 106. This change in temperature of the element 106 will move the

valve member 73 relative to the port 74 modulating the fuel flow according to air flow.

After a predetermined time interval, the burner will have heated the space in which the thermostat 123 is positioned to a sufficiently high temperature to cause the bimetallic blade 131 to move the contact member 130 out of engagement with the contact member 129, thereby deenergizing both the secondary circuits. Upon deenergization of the resistance unit 114, the cylindrical portion 107 will cool and decrease in temperature so that the lip portion 108 will be moved downward, moving the valve member 73 toward closed position until the lip portion 108 engages the flange 112 of the intermediate fire adjustment member 111. Meanwhile, the unit 113 and the cylindrical portion 92 having increased to a substantially higher temperature than the temperature reached by the unit 114 and cylindrical portion 107 reduces in temperature so that a short time after the lip portion 108 has engaged the flange 112 the lip portion 95 will engage the shoulder 80. Continued cooling of the cylindrical portion 92 will act to move the valve member 73 further toward closed position. Substantially at the same time the lip portion 95 engaged the shoulder 80, the lip portion 95 also engaged the shoulder 90 so that as the valve member 73 was moved towards closed position, the thrust member 86 was moved downward causing engagement of the shoulder 85 with the top surface of the plate-like member 81 and causing the switch 101 to be moved to open circuit position deenergizing the circuit to the motor 71 and reducing the supply of air through the duct 72 to the burner.

It may now be seen that with the apparatus as shown in Fig. 2 and with the room thermostat 123 satisfied, i. e., open circuit position, there will be no heaters actuated and the motor 71 will be deenergized. Upon dissatisfaction of the thermostat 123, i. e., engagement of the contact members 129, 130, the burner will be placed in operation and the unit 115 will act to modulate the flow of fuel controlled by the valve member 73 in accordance with the air supplied by the fan means 10 to maintain a predetermined desired fuel air ratio at the burner. This apparatus also acts as a safety device to prevent high fire fuel flow before high fire air flow and in the event of failure of high fire air flow to automatically reduce the fuel flow to that flow which will burn by natural draft.

What is claimed and is desired to be secured by Letters Patent of the United States is:

1. In an apparatus of the character described, a fluid fuel burner, means controlling the supply to said burner of a combustion supporting fluid medium, electric resistance means positioned in the path of flow of at least a portion of the fluid medium and having its resistance responsive to the cooling effect caused by the flow of the fluid medium, fuel supply controlling means for said burner, heat operated means for actuating said fuel supply controlling means, and electric heating means heated in accordance with the resistance of said electric resistance means and controlling said heat operated means thereby to actuate said last-named controlling means in proportion to the cooling effect of the fluid medium flow.

2. In an apparatus for supplying fluid fuel and air to a burner, a first electric resistance unit having a high coefficient of resistance with increase in temperature, a second electric resistance unit having a relatively low coefficient of

resistance with increase in temperature, circuit means connecting said first and said second units in series, means for supplying combustion supporting air, said first unit being positioned to be cooled by flow of the combustion supporting air thereby to decrease the voltage drop thereacross and to increase the voltage drop across said second unit, fluid fuel supply controlling means, heat responsive means for operating said controlling means in response to the heating effect of said second unit, said second unit acting to heat said responsive means in inverse ratio to the temperature of said first unit thereby to proportion the air and fuel.

3. In a control system for a fluid fuel burner, an electrically operated air supplying means for the burner, means for supplying fuel to the burner, flow regulating means intercalated in said fuel supplying means, a first control means for said flow means, a switch actuated by said control means upon actuation of said flow means toward an increased fuel flow, a first circuit means electrically connecting said switch to said air means and operable to energize said air means upon actuation of said switch, a heat actuated control means for said flow means and operable in one position to limit the amount of said increased fuel flow and operable in a second position to actuate said flow means for a further increased fuel flow, an electric resistance unit positioned to heat said heat actuated means and having a low coefficient of increase in resistance upon increase in temperature, a second electric resistance unit positioned in the air path of said air supplying means and operable to be cooled by air flow, said second resistance unit having a high coefficient of increase in resistance upon increase in temperature, a second circuit means connecting said resistance units in series circuit, and control means for said first circuit means.

4. In a control system for a fluid fuel burner, means for supplying air under pressure to the burner, means controlling the flow of air to be supplied by said air means to the burner, movable means controlling the supply of fuel to the burner, a heat actuated power element operatively connected to and for moving said movable controlling means, a first electric resistance unit positioned in heat exchange relationship with said power element and having a low coefficient of increase in resistance with increase in temperature, a second resistance unit having a high coefficient of increase in resistance with increase in temperature and positioned in the path of air flow supplied by said air means to the burner, a source of electric potential having a substantially constant value, and circuit means connecting said units in series circuit with each other and with said source of potential.

5. In a fluid fuel burner control system, means supplying air to the burner under pressure, means controlling flow of fuel to the burner and having an operating portion, a first resistance member positioned in the path of and cooled by the air supplied by said air means and having a high coefficient of resistance with increase in temperature, a heat actuated power element operatively connected to said operating portion and operable to actuate said flow controlling means, a second resistance member positioned in heat exchange relation with and for heating said power element, said second resistance member having a low increase in coefficient of resistance to electric flow with increasing temperature, an electric circuit connecting said resistance mem-

bers in series, the coefficient of resistance of said resistance members being so proportioned relative to each other that said first resistance member acts to vary the heat supplied to said power element in proportion to the air supplied to the burner thereby to maintain the desired fuel and air flow ratio to the burner.

6. In a fluid fuel burner control system, means for supplying air to the burner under pressure, means controlling flow of fuel to the burner and having an operating portion, electric current controlling means cooled by at least a portion of the air supplied by said air means and operable to modulate a flow of electric current in proportion to air flow through said air supplying means, an electrically operated power element operatively connected to said operating portion and operable to actuate said flow controlling means in proportion to the current flow through said element, an electric circuit connecting said electrically operated element and said electric controlling means, said current controlling means acting to modulate the electric current supplied to said electrically operated element proportionately to the rate of air flow supplied by said air supplying means thereby to maintain the desired fuel and air flow ratio to the burner.

7. In a fluid fuel burner control system, means for supplying air to the burner under pressure, means controlling flow of fuel to the burner and having an operating portion, electric current controlling means positioned in the path of and cooled by the air supplied by said air means and operable to modulate a flow of electric current in proportion to air flow through said air supplying means, a heat actuated power element operatively connected to said operating portion and operable to actuate said flow controlling means, a resistance member positioned in heat exchange relation with and for heating said power element, an electric circuit connecting said resistance member and said electric controlling means in series, said current controlling means acting to modulate the electric current supplied to said resistance member proportionately to the rate of air flow supplied by said air supplying means thereby to vary the heat supplied to said power element to maintain the desired fuel and air flow ratio to the burner.

8. In a fluid fuel burner control system, means for supplying air to the burner under pressure, means controlling flow of fuel to the burner and having an operating portion, electric current controlling means positioned in the path of and cooled by the air supplied by said air means and operable to modulate a flow of electric current in proportion to air flow through said air supplying means, a heat actuated power element operatively connected to said operating portion and operable to actuate said flow controlling means, a resistance member positioned in heat exchange relation with and for heating said power element, an electric circuit connecting said resistance member and said electric controlling means, said current controlling means acting to modulate the electric current supplied to said resistance member proportionately to the rate of air flow supplied by said air supplying means thereby to vary the heat supplied to said power element to maintain a desired fuel and air flow ratio to the burner.

9. In a fluid fuel burner control system, means for supplying air to the burner under pressure, damper means controlling the air supplied by said supplying means, means responsive to the

temperature of a space heated by the burner and operable to acutate said damper means, means controlling flow of fuel to the burner and having an operating portion, electric current controlling means positioned in the path of the air supplied by said air means to the burner and operable to modulate a flow of electric current in proportion to air flow to the burner, a heat actuated power element operatively connected to said operating portion and operable to actuate said flow controlling means, a resistance member positioned in heat exchange relation with and for heating said power element, an electric circuit connecting said resistance member and said electric controlling means, said current controlling means acting to modulate the electric current supplied to said resistance member proportionately to the rate of air flow supplied to the burner thereby to vary the heat supplied to said power element to maintain a desired fuel and air flow ratio to the burner.

10. In an apparatus of the character described a fluid fuel burner, fluid propelling means controlling the supply to said burner of a combustion supporting fluid medium, electrically heated means positioned in the path of flow of at least a portion of the fluid medium and cooled by the flow of the fluid medium thereover, fuel controlling means for supplying fuel to said burner, and bimetallic heat actuated means for controlling said fuel controlling means and controlled by said electrically heated means, said electrically heated means being operable to reduce the heat supplied to said bimetallic heat means thereby to regulate the fuel supplied to said burner in accordance with the fluid medium supplied to said burner.

11. A heating apparatus comprising a fluid fuel burner, a duct to supply combustion supporting air to said burner, means controlling air flow through said duct, a bimetal heat motor controlling said controlling means, an electric heater for actuating said heat motor, a thermostat controlling the circuit of said heater, a fuel valve controlling the supply of fuel to said burner, a bimetal heat motor controlling valve, an electric heater for operating said valve motor, an electric resistance member in said duct and cooled by air flow to said burner, electric circuit means including said second-named electric heater and said resistance member, said resistance member controlling the current flow to said valve motor electric heater thereby to control the ratio of fuel to air supplied to said burner.

12. A heating apparatus comprising a fluid fuel burner, a duct to supply combustion supporting air to said burner, a motor driven fan controlling air flow through said duct, a switch controlling the circuit of said fan, a bimetal heat motor for closing said switch, an electric heater for actuating said heat motor, a thermostat controlling the circuit of said heater, a fuel valve controlling the supply of fuel to said burner, a bimetal heat motor controlling said valve, an electric heater for operating said valve motor, an electric resistance member in said duct and cooled by air flow to said burner, electric circuit means including said second-named electric heater and said resistance member, said resistance member controlling the current flow to said valve motor electric heater thereby to control the ratio of fuel to air supplied to said burner.

13. A heating apparatus comprising a fluid fuel burner, a duct to supply combustion supporting air to said burner, a fan for supplying air to said

duct, a damper controlling air flow through said duct, a bimetal heat motor controlling the position of said damper, an electric heater for actuating said heat motor, a thermostat controlling the circuit of said heater, a fuel valve controlling the supply of fuel to said burner, a bimetal heat motor controlling said valve, an electric heater for operating said valve motor, an electric resistance member in said duct and cooled by air flow

5 to said burner, electric circuit means including said second-named electric heater and said resistance member, said resistance member controlling the current flow to said valve motor electric heater thereby to control the ratio of fuel to air supplied to said burner.
